Patented Oct. 30, 1917.

Fig. 4

UNITED STATES PATENT OFFICE.

GEORGE O. P. FLANDERS, OF EAST ARLINGTON, VERMONT.

MIRROR-BRACKET.

1,244,973.

Specification of Letters Patent. Patented Oct. 30, 1917.

Application filed May 5, 1917. Serial No. 136,547.

To all whom it may concern:

Be it known that I, GEORGE O. P. FLANDERS, a citizen of the United States, residing at East Arlington, in the county of Bennington and State of Vermont, have invented an Improvement in Mirror-Brackets, of which the following is a specification.

This invention relates to a mirror bracket particularly adapted for toilet purposes, 10 such as shaving for example, and is so constructed as to be readily secured in position on the casing of a window, jamb of a door, the rail of a window, or other similar places, and as readily adjusted to the position for 15 use. I am aware that heretofore various devices have been constructed for supporting mirrors for similar uses, but in all of these so far as has come to my knowledge, it has been either necessary to permanently mount them in place or to so construct them as to make them adapted to be placed in certain fixed positions. The 20 principal object of my invention is the provision of a mirror bracket the base of which 25 may be readily secured in position against any window casing, door jamb, or similar place, and as easily removed therefrom, the same being adapted to be attached to any ordinary window casing or door jamb and 30 when secured against the same, the other parts of the bracket may be adjusted to position for use. The parts are also so constructed as to be readily foldable to assume a relatively small space so as to be carried 35 about in grips or hand bags by travelers with as little inconvenience as possible, and at the same time the device may be set up for use at a moment's notice and at any place.

40 In carrying out this invention I preferably employ a base bar adapted at its extremities to engage the sides of a window casing, door jamb, or similar place, an arm which is pivotally mounted in the base bar 45 and revoluble to position therein, means being provided to maintain the arm in any required position, together with a series of rods preferably connected pivotally together, and also at one end to the arm, while 50 at the other they are adapted to support a mirror or other similar device as will be hereinafter more particularly described.

In the drawing:

Figure 1 is an elevation illustrating the 55 use of my improved mirror bracket.

Fig. 2 is an enlarged front elevation of the same showing the parts folded together when not in use and illustrating the mirror in dotted or broken lines.

Fig. 3 is a plan view of the bracket illustrating the parts in the position assumed in Fig. 1, and

Fig. 4 is an enlarged cross section on line 4—4 Fig. 3.

Referring to the drawing it will be seen 65 that in carrying out my invention I employ a base bar 10 which may be made of metal or any similar material, the ends 11 and 12 of which are overturned and pointed or sharpened at opposite angles as indicated 70 at 13 and 14; that is to say, the point 13 is directed toward one side of the base bar while the point 14 is directed toward the opposite side thereof. The distance between these pointed ends of the base bar is normally greater than the ordinary distance 75 between the sides of a window casing, a door jamb, a window rail, or other similar structure so that this base bar may be placed against the face of the window casing, for example, as indicated in Fig. 1, and turned so as to insert the pointed ends into the sides of the window casing in order to support the apparatus, it being understood 80 that it is only necessary to cause the points 85 to penetrate the side of the casing a relatively small distance in order to secure the bracket in position for use.

As clearly indicated in Fig. 4, the base bar 10 is centrally provided with a plate 15 90 which is secured thereto by rivets 16 or otherwise. The arm 17 is pivotally connected in the plate 15 as indicated at 18 and fixed on this pivotal point or to the plate 15 is a ratchet 19. The arm 17 carries a pawl 20 which may be secured thereto by a stud 21 or otherwise around which one end of the pawl passes, while at its opposite end this pawl is adapted to engage the teeth of the ratchet 19.

On the face of the arm 17 there is a pin 22 to which at one end a rod 23 is pivotally connected. Also on the outer face of the arm 17 is a stop 24 which acts to limit the swinging movement of the rod 23 and also 105 to support the same together with the rods 25 and 26 which are pivotally connected to one another and to the rod 23 as indicated at 27 and 28, while the outer or free end of the rod 26 is upturned or bent at an angle 110

2 to the greater portion of the rod as indicated at 29, and adapted to pass through suitable openings provided therefor in the bracket 30 on the reverse side of a mirror 31. 5 The hereinbefore described apparatus may be folded with the arm 17 lying in line with the base bar 10 and the rods 23, 25 and 26 folded together to assume the position shown in Fig. 2, when of course the mirror may be 10 disconnected and kept in a separate place. When using the apparatus the parts are unfolded and the base bar placed against a window frame 32, for example, with the inner face of the bar against the surface of 15 the casing, and the points 13 and 14 of the overturned ends of the bar forced into the sides of the casing by a slight twisting movement of the base bar. This as understood will be possible irrespective of the 20 width of the window casing so long as the same is not wider than the distance between the points on the end of the base bar. On the base bar thus adjusted, the arm 17 may be turned counterclock-wise to such a position 25 that the rod 23 will be substantially horizontal when as will be understood, the arms 25 and 26 may be adjusted on each other to assume any desired position supporting the mirror 31 at the free end thereof.

30 I claim as my invention:

1. A mirror bracket comprising a base bar having ends overturned in opposite directions and pointed so as to engage the sides of a window casing or similar structure, 35 an arm mounted in said base bar, and rods connected to one another and at one end secured to the said arm and at the other end adapted to support the mirror.

2. A mirror bracket comprising a base 40 bar having ends overturned in opposite directions and pointed to engage the sides of a window casing or similar structure, an arm pivotally mounted in said base bar, means for maintaining said arm in different positions relatively to the base bar, and rods pivotally connected to one another and at

one end secured in the said arm and at the other end adapted to support a mirror.

3. A mirror bracket comprising a base bar having its ends overturned in opposite 50 directions and pointed so as to grip the opposite sides of a window casing or similar structure, an arm pivotally mounted in the said base bar, a ratchet secured to the base bar, a pawl carried by the arm for supporting the same in any desired position relatively to the base bar, and a series of rods pivoted together and secured at one end in the said arm and at the opposite end adapted to support a mirror.

4. A mirror bracket comprising a base bar having its ends overturned in opposite directions and pointed so as to grip the opposite sides of a window casing or similar structure, an arm pivotally mounted in the 65 said base bar, a ratchet secured to the base bar, a pawl carried by the arm for supporting the same in any desired position relatively to the base bar, a series of rods pivoted together and secured at one end in the 70 said arm and at the opposite end adapted to support a mirror, and a stop fixed in the said arm for determining the position of the said rods.

5. A mirror bracket comprising a base bar 75 having its ends overturned in opposite directions and pointed so as to grip the opposite sides of a window casing or similar structure, an arm pivotally mounted in the said base bar, a ratchet secured to the base 80 bar, a pawl carried by the arm for supporting the same in any desired position relatively to the base bar, a series of rods pivotally connected together and at one end pivotally connected to the said arm, the opposite end of the said rods being upturned 85 to receive and support a mirror, and a stop for determining the position of the said rod which is pivotally connected to the arm.

Signed by me this 16th day of April 1917. 90

GEO. O. P. FLANDERS.
